(57) **CLAIM**

The ornamental design for a hat, as shown.

DESCRIPTION

FIG. 1 is a left side elevational view of the hat, showing my design;

FIG. 2 is a front view thereof;

FIG. 3 is a right side elevational view thereof;

FIG. 4 is a top plan view thereof;

FIG. 5 is a rear view thereof; and,

FIG. 6 is a bottom plan view thereof.

In the drawings, the broken lines on the headband represent stitching forming part of the claimed design. All other broken lines represent environmental structure forming no part of the claim.
